UNITED STATES PATENT OFFICE

FRANK X. WIESHUBER, OF CHICAGO, ILLINOIS

DESIGN FOR A TOY WHISTLE

Application filed March 23, 1932. Serial No. 43,270. Term of patent 3½ years.

To all whom it may concern:

Be it known that I, FRANK X. WIESHUBER, a citizen of the United States, residing at Chicago, in the county of Cook and State of Illinois, have invented a new, original and ornamental Design for a Toy Whistle, of which the following is a specification, reference being had to the accompanying drawing, forming part thereof.

I claim:

The ornamental design for a toy whistle as shown.

FRANK X. WIESHUBER.
